UNITED STATES PATENT OFFICE.

JOHN JACOB EARGLE, OF NEWBERRY, SOUTH CAROLINA.

DESIGN FOR A CHIMNEY.

48,818.

Specification for Design.

Patented Apr. 4, 1916.

Application filed September 1, 1915. Serial No. 48,556. Term of patent 14 years.

To all whom it may concern:

Be it known that I, JOHN J. EARGLE, a citizen of the United States, residing at Newberry, in the county of Newberry and State of South Carolina, have invented a new, original, and ornamental Design for Chimneys, of which the following is a specification, reference being had to the accompanying drawing, forming a part thereof.

The figure is a perspective view of a chimney, showing my new design.

I claim:

The ornamental design for a chimney, as shown.

JOHN JACOB EARGLE.

Witnesses:

H. C. HOLLOWAY,
B. V. CHAPMAN.
